UNITED STATES PATENT OFFICE.

ARTHUR W. HARRISON, OF WINTHROP, MASSACHUSETTS, ASSIGNOR, BY MESNE ASSIGNMENTS, TO PORCELAIN APPLIANCE CORPORATION, OF WILMINGTON, DELAWARE, A CORPORATION OF DELAWARE.

ATTACHING DEVICE.

Application filed June 6, 1918. Serial No. 238,559.

To all whom it may concern:

Be it known that I, ARTHUR W. HARRISON, a citizen of the United States, and resident of Winthrop, in the county of Suffolk and State of Massachusetts, have invented certain new and useful Improvements in Attaching Devices, of which the following is a specification.

This invention relates to means for holding, in assembled condition, apertured members such as knobs for electrical work, and attaching members such as nails or screws, so that the assembled devices can be shipped and sold and eventually fixed in desired positions by the workmen, the complementary members of each device retaining such relative positions that the workman will not be obliged to search for and assemble cooperating members.

Several devices for this purpose have been produced, one contemplating the swedging or striking up of portions of the nails or screws, and another the employment of washers slipped onto the nails or screws. So far as I am aware, every prior device for this purpose has required that some operation be performed after the attaching member has been passed through the aperture of the other member.

The object of my invention is to provide devices of the character described which, as the result of simply assembling them by passing the attaching members through the apertures of the cooperating or complementary members, will remain assembled during shipment and handling without requiring any further operation or the application of any third member.

To this end, my invention consists in the device or combination of members substantially as hereinafter described and claimed.

Of the accompanying drawings:

Figure 1 is vertical section of a device embodying my invention;

Figure 2 is a plan of another form;

Figure 3 is a vertical section of the form illustrated in Figure 2;

Figure 4 is a section of a two-piece knob;

Figure 5 is an elevation of the same with the two pieces in juxtaposition and showing the support in section.

Figure 6 is an illustration of another way of forming the attaching member with an elastic or compressible shoulder.

In Figure 1, I show a porcelain member A having an aperture a for the reception of a nail a' which however might be a screw. Said nail or screw, comprising the attaching member of the device is elastically enlarged at a proper distance from its head, as by cutting into one or more of its sides to form one or more prongs or protuberances a^2 the tips of which extend toward the head end of the attaching member. When the screw or nail is passed through the aperture a , the elastic prongs or enlargement is automatically collapsed until it is passed entirely through when it automatically enlarges or springs out so that its tip engages the base of the porcelain member and effects retention of the porcelain member and the attaching member in proper but loose relative positions. Of course the elastic portion of the attaching member is normally of greater diameter than the aperture or passage a .

It will be seen that the head of the screw or nail, as well as the elastic portion thereof are of greater transverse dimension than the passage a so that the attaching member A can not be accidentally separated from member A.

If desired a washer a^4 of leather or other suitable material may be employed under the head of the attaching member, the chief object of this being to prevent cracking of the member A by the head of the attaching member. This form of my invention is particularly useful as a hanger for the wires of pictures although of course member A may be of any desired form or material or used for any desired purpose.

In Figures 2 and 3 I illustrate a one-piece insulator B having a skirt b^7 and having passageways b^8 and lips b^9 to keep the wires in place. Passage b^2 receives nail b^3 which has elastic protuberances or shoulders b^2 as in Figure 1, and the relative transverse dimensions of the passage b^2 and the head of the nail, and the elastic protuberances being as in Figure 1.

In Figure 4 I show a knob comprising two complementary pieces or portions D and D', the latter having a skirt d , a passage d' , an insulating boss d^2 and two grooves d^3 and d^4 to receive wires d^5 , d^6 . Portion D has two grooves d^5 and d^6 to receive wires d^7 , d^8 (Fig. 5) and recess d^8 to receive boss d^2 , and

also has passage d^0 in registry with passage d^1 . Whether the device be as illustrated in Figures 1 or 3 or 4, I may employ only one elastic protuberance a^2 as shown in Figure 4 5 instead of two as shown in Figures 1 and 3.

In Figure 5 the two pieces of the knob are in juxtaposition engaging the wires d^1 d^2 while in Figure 4 the two pieces are separated for manipulation of the wires. E 10 is the support which may be a wall or ceiling, for example. In Figure 5 it will be clear that the boss d^2 insulates the nail from the wires d^1 d^2 .

It will thus be seen that in Figures 4 and 15 5 the two pieces are not only held against undesired separation, although they may be freely moved somewhat relatively for manipulation of the wires, but the two pieces are prevented from separation from the attaching member shown in these figures as a nail.

I do not limit myself to constructing the attaching member with an elastic protuberance consisting of one or more backwardly extending portions the ends of which are 25 free. As shown in Figure 6, the attaching nail or screw C may be split at the proper point as at c, and spread so as to form two elastic surfaces c' c' .

In all the forms so far described the 30 washer for the head of the attaching member will be placed in position and then the attaching member will be pushed through the passage or aperture, the elastic portion or protuberance yielding sufficiently to permit this to be done, the said elastic protuberance being capable of then expanding to a point beyond the diameter of the passage.

Swedging or striking up of a portion of an 40 attaching member results in forming an in- elastic protuberance which, in order to pass through the aperture of an insulating mem- ber, must not exceed the diameter of such

aperture, or else it must be formed or enlarged after assembling. In one case it is necessary to add a third member such as a washer of some kind, and in the other case mechanical treatment is required after assembling. It will be understood that by my invention no treatment after assembling is required, and the addition of no third member is necessary.

If a porcelain member should be broken, it is possible to replace it with an unbroken one. For instance if a cap member D is struck by the hammer of the workman when driving the nail, he can pull the nail out from the wall or other support, compress the prong a^2 sufficiently to enable him to slip the base member D' off, and then reassemble the nail and base member with a new cap member D.

I do not limit myself to making the protuberances or barbs a^2 by cutting into the sides of the nails, as they may be otherwise formed or may be small pieces of resilient metal attached to the nails in any well-known manner.

What I claim is:

As an article of manufacture for the purpose described, the combination with a vitreous member having a passage, of a rigid attaching member extending through said passage, said attaching member having a head at one end and a point at the other end and also having an integral prong of elastic material extending with its tip toward the said head, and the attaching member at the point where said prong is located being normally larger than said passage, the vitreous member being loosely retained on the attaching member by said head and prong.

In testimony whereof I have affixed my signature.

ARTHUR W. HARRISON.
